CASHIER'S ROBBERY PROTECTOR

Filed April 8, 1926

HENRY HAGESTEDT

FIG. 6. *Milo B. Stevens & Co.*
ATTORNEYS

Patented Apr. 5, 1927.

1,623,674

UNITED STATES PATENT OFFICE.

HENRY HAGESTEDT, OF CHICAGO, ILLINOIS.

CASHIER'S ROBBERY PROTECTOR.

Application filed April 8, 1926. Serial No. 100,741.

My invention relates to improvements in protective window constructions for bank tellers and the like and has for its primary object to provide a relatively simple device of this character which will be highly efficient in practical use; capable of ready installation without materially altering conventional window constructions; and one including a novel form of sectional protective screen which will occupy a very small space when not in use but which can be positively and instantaneously actuated to effective position in an emergency.

The invention also comprehends certain other objects and advantages which will be developed in the course of the following descriptive matter. The various features of novelty are pointed out with particularity in the claims annexed to and forming a part of this specification. The accompanying drawings illustrate what I now regard as a preferred embodiment of the invention, but I am aware that I may make such minor changes therein as do not depart from the spirit and scope of the invention as claimed.

In the drawings,

Figure 1 is an elevation, partly in section and partly broken illustrating a window embodying my invention;

Figure 2 is a section on the line 2—2 of Fig. 1;

Figure 3 is a view similar to Fig. 2 but illustrating the screen sections in effective position;

Figure 4 is a detailed sectional view of a latch actuating weight and an electro-responsive releasing device therefor;

Figure 5 is a sectional detail of the latch in holding engagement with a screen section, and

Figure 6 is a fragmentary perspective of the upper end of one of the screen sections.

Referring specifically to the drawing, wherein, like reference characters designate similar parts in all views, numeral 1 indicates the cashier's window which is provided with a counter 2, the lower wall section 3 beneath the counter being provided with a bullet resisting screen 3^a.

The window jambs are provided with grooves 4 in which are designed to slide screen sections 5. Each of the screen sections is of S-shaped formation, that is, each end is formed with hooks 5^a. One of the sections 5 has its upper reverted hook end

fixed to the upper window frame as indicated at 6. The other screen sections 5 are mounted to slide in the frame groove 4, and as clearly shown in Fig. 3, the upper and lower hooks 5^a interengage as the screens descend to form a protective barrier for the cashier.

The outermost, or as shown in Fig. 3, the lower of the slide sections 5 differs from its fellows in that its lower end is straight and is designed to engage in a slot 7 in the counter 2. There is also provided on the counter a spring latch 8, the nose of which is designed to engage a lug 9 projecting from the said outer screen section 5.

Fig. 2 aptly illustrates the manner in which the slide sections 5 are held in a nested position in the upper ends of the grooves 4. It will be observed from an inspection of this figure that each slide section has a laterally projecting tongue 5^b, which frictionally engages the lower curved end of the next adjacent section to yieldingly hold it against descent. There is provided in the window jambs, as shown in Fig. 1 and also in Fig. 5, a pivoted latch 10 whose upper end engages the tongue 5^b of the outermost section 5.

The latches 10 are maintained in effective position by means of coil springs 11, carried by a cross member 12 as shown in Fig. 5. It is seen that each jamb is cut with a slot 13 to receive a latch 10. The means for releasing the latches 10 comprehends an electric solenoid 14 whose casing is secured beneath the counter 2 and located for convenient operation by the cashier.

The end of the solenoid plunger 14^a projects through the casing or housing to engage the lateral end 15^a of a rod 15 which is fastened in any desired manner to a weight 16 located for sliding movement in a cylinder 17. The said cylinder 17 is attached to the counter by means of a bracket 17^a or otherwise as may be found expedient. To the weight 16 are fastened the ends of chains 17, which pass upwardly in the cylinder and laterally over pulleys 18 and through the jambs or sides of the window frame beneath the counter. As shown in Fig. 1, the chains 17 are also trained over pulleys 19 and 20 which latter are aligned with the slots 13, the ends of said chains engaging latch members 10. It is evident that upon energization of the solenoid 14 the weight 16 will be released and the latches

pulled outwardly to allow the screen sections position, flexible members connected to one 5 to descend into the position shown in of the closure sections adjacent the ends thereof, said flexible members having their lower ends provided with evenly balanced 45 Fig. 3.

To accelerate the movement of the weight 16, whereby to more quickly release the latches 10, I have provided a coil spring 21, shown in Fig. 4, which bears upon the weight and against a circumferential flange at the upper end of cylinder 16. At either 10 side of the lower edge of the outermost screen section 5 there is secured a chain 22 which is concealed in the jamb and has its lower end secured to a weight 23 working in a guide column 24. Each guide column 24 15 has an apertured closure cap 25 through which the chain passes. Thus it will be apparent that the weights 23 assure the immediate actuation of the sections 5 to the position shown in Fig. 3, when the latches 20 10 have been released. The movement of the weights 23 is augmented by the coil springs 26 engaging the weights and the closure caps 25.

From the foregoing it will be evident that 25 the cashier's window will present the usual appearance and will in no way suggest the presence of my improved protective screen. The engagement of the lower end of the outermost screen section 5 in the counter 30 slot 7 and the engagement of the lug 9 by the latch 8 prevents an intruder from forcing the screen open.

Having thus described my invention, what I claim as new and desire to secure by 35 Letters Patent, is:—

1. A device of the character described comprising a frame, a closure carried there-by and consisting of a plurality of inde-pendent sections slidably mounted in said frame and having interlocking portions, a latch normally holding said closure in open

weights, separate barrels receiving said weights and portions of said flexible mem bers, and springs in said barrels and adapt ed to urge said weights downwardly upon the release of said latch whereby to forcibly 50 advance said closure to its closed position.

2. A device of the character described comprising a frame, a closure carried there-by and consisting of a plurality of inde-pendent sections slidably mounted in said frame and having interlocking portions, latches carried by the opposite sides of said frame and normally holding said closure in an open position, flexible members connected to said latches and having their lower ends 60 connected to a weight, a barrel receiving said weight, a plunger adjacent said barrel, means carried by said weight and engage-able with said plunger for normally main-taining said weight in an elevated position, a 65 spring in said barrel and urging said weight downwardly upon the release of said plunger from engagement with said weight carried means to retract said latches, flexible mem bers connected to one of the closure sections 70 adjacent the ends thereof, said second-named flexible members having their lower ends provided with evenly balanced weights, sep-are barrels receiving said weights and portions of said second-named flexible mem bers, and springs in said barrels and urging said weights downwardly upon the release of said latches whereby to forcibly advance said closure to its closed position.

In testimony whereof I affix my signature.

HENRY HAGESTEDT.
